H. SWARTZ

COAL GAS CARBURETOR

Original Filed July 20, 1921

FIG. I.

FIG. II.

*by Arthur E. Raige,
Attorney.*

UNITED STATES PATENT OFFICE.

HENRY SWARTZ, OF PHILADELPHIA, PENNSYLVANIA.

COAL-GAS CARBURETOR.

Application filed July 20, 1921, Serial No. 468,127. Renewed November 17, 1923.

To all whom it may concern:

Be it known that I, HENRY SWARTZ, a citizen of the United States, residing at Philadelphia, in the county of Philadelphia and State of Pennsylvania, have invented a certain new and useful Improvement in Coal-Gas Carburetors, whereof the following is a specification, reference being had to the accompanying drawing.

10 My invention relates to devices designed to mix atmospheric air with the gaseous primary products of combustion from a coal fire, to facilitate the complete combustion of such products and consequent economy 15 of fuel.

The form of my invention hereinafter described is adapted as an accessory attachment for an ordinary house cooking range or stove. However, it is to be understood 20 that it may be employed in conjunction with any type of furnace.

As hereinafter described; my improved device includes a tubular air conduit having means to rigidly secure it at an opening 25 extending through an ordinary stove lid; said conduit carrying, at its inner end, a mixing retort with an air inlet and outlets, and having, at its outer end, means adapted to afford a permanent air inlet 30 port of predetermined size.

I am aware that it is not broadly new to provide a stove lid with means to admit air therethrough. However, as ordinarily constructed, such devices serve to check 35 combustion rather than to aid combustion; for the reason that unless the air thus admitted is intimately mixed with the combustible primary products of combustion of the coal, and in such proximity to the coal 40 that said products are at the proper temperature for reaction with the oxygen of the air; the latter merely cools said products and prevents their combustion; so that they pass to the flue merely diluted and un- 45 consumed.

Moreover, such devices of the prior art, applied to stove lids, interfere with the ordinary use of the stove in which they are embodied for the reason that they either 50 project above the lid so as to prevent placement of an ordinary flat bottomed cooking utensil on the lid, or are so arranged that the air supplied through them cools the lid and thus prevents it from being used to

heat such a cooking utensil, and many of 55 the devices of the prior art have both those defects.

Therefore, it is an object and effect of my invention to provide such a coal gas carburetor as may be readily applied to 60 an ordinary stove lid without lessening the ordinary utility of such a lid for supporting such cooking utensils and heating them; incidentally leaving the outer surface of 65 the lid in its normal continuously plane state and leaving the inner surface of the lid exposed to the heat from the fire, except at a negligibly small spot where the carburetor is attached.

My invention includes the various novel 70 features of construction and arrangement hereinafter more definitely specified.

In said drawing; Fig. I is a plan view of an ordinary circular stove lid with a convenient embodiment of my invention applied thereto.

Fig. II is a vertical transverse sectional view of the lid and carburetor shown in Fig. I, with a fragmentary sectional view of a portion of the stove or furnace casting adapted to support said lid.

In said figures; the stove lid 1 is of the ordinary plane construction and includes the circumferential flanges 2 and 3 fitted to the corresponding seat 4 in the stove or furnace wall plate 5, inclosing the fire chamber 6. I provide said lid 1 with the central opening 7 to receive the tubular screw 8 having the flat topped conical head 9, flush with the outer plane surface of 90 said lid 1; said head fitting a corresponding conical seat in said lid 1. Said screw 8 has the axial air passage 10 and forms a tubular air inlet conduit which rigidly connects said lid 1 with the screw threaded neck 11 of the retort 12. Said retort is conveniently formed as an oblate sphere, inclosing the mixing chamber 13 and may be formed of a single casting of iron, which 95 may be alloyed with silicon and manganese in such proportions as to resist oxidation. Said retort 12 overhangs the fire 14, as indicated in Fig. II, so as to extend within the gaseous primary products of combustion 15 arising from said fire. Said retort 12 has 100 at its bottom, a circular series of nozzles 17 which, as shown in Fig. II, have respective cylindrical vents 18 outwardly flared

100

105

at their outer ends. It may be observed that said vents 18 are in parallel relation with each other and with the axis of the tubular air inlet conduit 8. However, they 5 may be otherwise grouped and arranged. I also find it convenient to provide said retort 12 with the baffle plate 20, in said chamber 13; which plate is substantially circular as indicated in Fig. I, and provided with the circumferential series of notches 21 through which the air passes downwardly from said inlet passageway 10 to said outlet nozzle vents 18.

Such baffle plates 20 may be formed of 15 stamped sheet, or cast metal primarily imbedded in any suitable frangible core sand composition, which is cast in said retort 12 to form said chamber 13 thereof; said core composition being subsequently shaken out, 20 and leaving said baffle plate 20 loose in said chamber 13, as shown. Such baffle plates are advantageously employed to insure intimate contact of the inflowing air with the hot metal walls of said retort 12, before 25 reaching said nozzle vents 18. However, it is to be understood that a coal gas carburetor may be made in accordance with my invention without such a baffle plate.

It is essential to the operation of my 30 invention for the purpose herein contemplated that it shall so feed air into intimate mixture with the gaseous fuel products as to facilitate further combustion of such products, and that result is attained by not only 35 preheating the air in said retort 12 which is pendent in said fire chamber 6, but by causing the air thus preheated to be forcibly injected, through said nozzle vents 18, into the flames arising from the coal. Of course, the 40 induction of air through such retorts is effected by the ordinary chimney draft of the stove or furnace in which my invention is embodied, but the injection of the air in jets with the proper force and in the proper direction is due to the construction and arrangement of said nozzles 17. For instance; if said nozzles were omitted and the air permitted to merely escape from said retort through apertures at the sides or top of 45 the latter, the air thus supplied to the fire chamber 6 might merely serve to lower the temperature of the contents of the latter, without facilitating combustion thereof; because of failure to mix with the primary 50 products of combustion in the proper place and at the proper temperature.

Of course, the form and proportion of the 55 retort elements of my invention should be determined by the construction and arrangement of the furnace in which they are to be employed. Therefore, I do not desire to limit myself to the precise details of construction and arrangement herein set forth, as it is obvious that various modifications 60 may be made therein without departing

from the essential features of my invention, as defined in the appended claims.

I claim:

1. The combination with a plane stove lid; having an opening therethrough with a 70 conical seat at the outer end of said opening; of a tubular air conduit having a flat slotted head at its outer end, fitted in said seat, and screw threaded at its inner end; a retort, of oblate spheroid form, formed of 75 a single casting, having a neck screw threaded to engage said tube, and rigidly connected by the latter to said lid; said retort inclosing a mixing chamber, supplied with air through said tube; said retort having a circular series of nozzles at the bottom thereof with vents extending therethrough; said series of vents being in parallel relation with each other and with the axis of said tube; and a loose circular baffle plate, in said 80 chamber, having a circumferential series of notches in its perimeter arranged to direct the air flowing from said tube to said nozzles in intimate contact with the wall 85 of said retort.

2. The combination with a plane stove lid; having an opening therethrough with a seat at the outer end of said opening; of a tubular air conduit having a head at its outer end, fitted in said seat, and screw 90 threaded at its inner end; a retort, having a neck screw threaded to engage said tube, and rigidly connected by the latter to said lid; said retort inclosing a mixing chamber, supplied with air through said tube; said retort having a group of nozzles with vents 95 extending therethrough; and a loose circular baffle plate, in said chamber, having a circumferential series of notches in its perimeter arranged to direct the air flowing 100 from said tube to said nozzles in intimate contact with the wall of said retort.

3. The combination with a plane stove lid; having an opening therethrough; of a tubular air conduit, in said opening, having its outer end flush with said lid; a retort, formed of a single casting, connected to said tube, and rigidly connected by the latter to said lid; said retort inclosing a mixing chamber, supplied with air through said tube; said 110 retort having a group of nozzles at the bottom thereof with vents extending therethrough; said series of vents being in parallel relation with each other and with the axis of said tube; and a circular baffle plate, 115 in said chamber, having a circumferential series of openings at its perimeter arranged to direct the air flowing from said tube to said nozzles in intimate contact with the wall of said retort; said vents being outwardly flared at their discharge ends.

4. The combination with a plane stove lid; having an opening therethrough; of a tubular air conduit in said opening, having its outer end flush with said lid; a retort, con- 120

ected to said tube, and rigidly connected by the latter to said lid; said retort inclosing a mixing chamber, supplied with air through said tube; said retort having a group of 5 nozzles at the bottom thereof with vents extending therethrough; and a circular baffle plate, in said chamber, having a circumferential series of openings at its perimeter arranged to direct the air flowing from said

tube to said nozzles in intimate contact with 10 the wall of said retort.

In testimony whereof, I have hereunto signed my name at Philadelphia, Pennsylvania, this 31st day of May, 1921.

HENRY SWARTZ.
